(57) **CLAIM**

The ornamental design for a three-head roller stamp set, as shown and described.

DESCRIPTION

FIG. 1 is a front elevation view of a three-head roller stamp set showing my new design with the remainder omitted in order to show aspects of the design not otherwise apparent; FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a right, top and front perspective view thereof;

FIG. 8 is a left, bottom, and rear perspective view thereof;

FIG. 9 is a front elevation view of a cap of the three-head roller stamp set showing my new design the remainder omitted in order to show aspects of the design not otherwise apparent;

FIG. 10 is a rear elevation view thereof;

FIG. 11 is a left side elevation view thereof;

FIG. 12 is a right side elevation view thereof;

FIG. 13 is a top plan view thereof;

FIG. 14 is a bottom plan view thereof

FIG. 15 is a right side, top, and front perspective view of another cap of the three-head roller stamp set showing my new design the remainder omitted in order to show aspects of the design not otherwise apparent;

FIG. 16 is a left side, bottom, and rear perspective view thereof; and,

FIG. 17 is a right side, top, and front perspective view of the three-head roller stamp set showing my new design in a combined state with the caps.

The broken lines immediately adjacent to the shaded areas depict the bounds of the claimed design, while all other broken lines are directed to environment. The broken lines form no part of the claimed design.

(Continued)

The diagonal hatching in the views represents reflective surfaces.
